UNITED STATES PATENT OFFICE.

HUGO A. HECKER, OF BELLEVUE, KENTUCKY, ASSIGNOR, BY MESNE ASSIGNMENTS, TO THE AMERICAN LAUNDRY MACHINERY MANUFACTURING COMPANY, A CORPORATION OF NEW JERSEY.

MANGLE.

No. 913,726.

Specification of Letters Patent. Patented March 2, 1909.

Application filed January 27, 1906. Serial No. 298,235.

To all whom it may concern:

Be it known that I, HUGO A. HECKER, a citizen of the United States, residing at Bellevue, in the county of Campbell and State of Kentucky, have invented certain new and useful Improvements in Mangles, of which the following is a specification.

It is the object of my invention to provide new and useful improvements whereby the capacity of mangles may be increased from time to time under retention of the original mangle and the addition of sections of mangles from time to time, while providing novel means between mangle-sections whereby differences or changes in alinement between adjacent edges of mangle-sections may be compensated for cheaply, readily and conveniently; in providing mangle-sections with flexible or resilient conforming bed-connections whereby variations between adjacent bed-surfaces of adjoining mangle-sections are readily, conveniently and cheaply overcome; further in new and improved means for guiding the material with relation to the rotating heating cylinder; and the invention will be further readily understood from the following description and claims, and from the drawings, in which latter:

Figure 1 is a side elevation of my improved device. Fig. 2 is a central longitudinal section of the same. Fig. 3 is a plan view showing adjacent or meeting ends between mangle-sections, the sections being partly broken away. Fig. 4 is a section of the same on the line $x-x$ of Fig. 3. Fig. 5 is a detail in section, on similar line, indicating sagged relation of one of the steam-chests. Fig. 6 is a central longitudinal section of the bridge-plate, partly broken away. Fig. 7 is a detail in section showing the manner of mounting the steam-chest rolls. Fig. 8 is a detail of frame-connection between mangle-sections. Fig. 9 is a plan view of the stock-guiding means for the steam cylinder, partly broken away. Fig. 10 is a section of the same on the line $y-y$ of Fig. 9. Fig. 11 is a detail in section on the line z of Fig. 10, showing the guide-plate adjusting means; and, Fig. 12 is a sectional detail showing manner of mounting the upper cylinder rolls.

My invention is particularly applicable to the character of mangles intended to be used in "flat work".

Y Z are mangle-sections, of which I shall designate the section Y the original section, and the section Z the added section, and in my improved device the section Y may form the completed mangle, whether with or without the steam cylinder hereinafter described, or there may be any desired number of these added sections in the composite completed mangle, and my improved construction is such that sections may be readily added, and the fit between sections readily obtained, from time to time, irrespective of differences in length of time of use between mangle-sections, and this feature is especially valuable as the steam-chests of mangles of this character are liable to and do warp in course of service, and it is essential to have a smooth surface without offsets between adjacent mangle-sections for forming a bed surface along which the goods may travel without meeting with obstruction.

The section Y may comprise a frame A containing heating or steam-chests B C suitably secured therein and having suitable supply and discharge openings for steam. Mangle rolls D E are suitably journaled with relation to the steam-chests and to the frame. These rolls are provided with a suitable compressible covering, and are received adjacent to the concave surfaces 1 of the steam or heating chests. If desired the section Y may also be provided with a rotating steam cylinder and co-operating apron therefor in manner hereafter described.

The rolls D E are suitably supported and driven as by providing each with a shaft 3 journaled in a bearing 4 slidable in guide-way 5 in the respective sides 6 of the frame A. The bearing has an upwardly extending rod 7 (see Fig. 7) pivoted thereto, said rod having set-nut 8 at its upper end which bears upon a lever 9 articulated with the frame by means of a link 10. The lever is provided with a pocket 11 in which there is a spring 12 bearing against the roll-bearing for permitting the roll to yield to variations in thickness of stock fed through the machine. For positioning the rolls with relation to the steam-chests, rods 15 for the respective levers are provided. Each of these rods has nuts 16 17 respectively above and below the swinging end of the lever and taking against curved surfaces 18 of the latter, these curved surfaces and the links 10 being

provided for permitting the roll bearings to be adjusted or to yield vertically without cramping the levers.

The screw rods 15 are held against rotating with relation to the frame by having a squared portion 19 thereon taking against a similar opening 20 in the frame, and are screw-threaded at their lower ends as shown at 21. The screw-rods 15 for the rolls of a given mangle-section are preferably adjacent each other and are received respectively into internally threaded worm-gears 22 23 meshing with an intermediate worm 24 on a shaft 25, said shaft having a corresponding worm at each side of the machine, there being corresponding screw-rods and levers for the bearings at each end of the mangle rolls for raising and lowering the bearings of both rolls simultaneously depending on the direction of rotation given the shaft 25 by the hand-wheel 26.

31 is a drive-shaft journaled in the frame A and having a gear 32 and a pinion 33 thereon, the pinion 33 meshing with an intermediate gear 34 on a stud 35, the said intermediate gear meshing with gears 36 37 respectively on the roll-shaft of rolls D E for driving the latter.

The added section Z has a frame A' containing heating or steam-chests B' C'. Mangle rolls D' E' with operating devices for the latter similar to those described with relation to the section Y, are provided, and it is therefore not necessary to particularly enumerate the same, but in the drawings they are indicated by similar reference letters and numerals, but provided with the exponent prime ('). The frame A' also has bearings 38 in which a shaft 39 is journaled, the shaft carrying the gear 40 which serves as a connecting gear between the driving gears of rolls E D'. The sides of the frame A are provided with meeting faces 42, and the sides of the frame A' with meeting faces 43 42'. The frame A is provided with lugs 44, (see Figs. 1 and 8), and the frame A' with lugs 45 44' similar to the lugs 44. Bolts 46 take through the lugs 44 45 and connect the frames A A', as through apertures in said lugs similar to the aperture shown in lug 44 in Fig. 8, nuts 46' being received over the threaded ends of the bolts. The frames are bolted together at both sides of the machine in the manner stated. Additional sections similar to the added section Z may be provided and added in advance of said section Z, these additional sections being constructed similarly to the added section Z. The frame A is provided with a tie-rod 47, and the frame A' is provided with a tie-rod 47'. Goods-receptacle F has hooks f taking over the tie-rod at the feeding-in-end of the machine, whether that feeding-in-end be at the beginning of section Y or Z or an additional section, and is

adapted to be readily slipped over the tie-rod of said end section, and is provided with adjusting bolts f' arranged to take against the frame of said end section.

It will be understood that in mangles of 70 this character the goods travel between the steam-chest and the rolls, and that the greater the number of rolls and steam-chests the larger will be the capacity of the machine in that the rolls may be driven at 75 greater speed. In order to insure correct travel of the goods it is essential that the surface upon which the goods travel shall be such that the goods may not be interrupted or caught. It will be further understood that the steam-chests are subjected to high and also varying degrees of temperature, and further that these chests are long bodies, sometimes a hundred inches or more in length, and that in practice they warp 80 or sag in varying degrees in course of use, bringing the longitudinal edges of the steam-chest out of original alinement. The result is that if it is attempted to mate a new section with one that has been in use, differences in alinement between the two will be 85 found, and if a mangle-section having a new steam-chest were attempted to be placed adjacent to a mangle-section already in use, the adjoining steam-chests will be out of 90 longitudinal alinement and prevent proper travel of the goods from one to the other, or necessitate expensive and tedious fitting away from the shop. To obviate these difficulties, I provide novel flexible or resilient 95 connection between mangle-sections. Thus G is a flexible or resilient plate which I prefer to perforate. I separate the adjacent longitudinal edges 51 52 of the respective steam-chests C B' of adjoining mangle-sections, and I provide the same with longitudinal rabbets 53 54 adapted to receive the longitudinal edges of the resilient plate G. I prefer to curve this plate and to reduce the upper faces of the rabbets toward their 100 outer edges for normally forming a slight space 55 between the outer edges of the bottom faces of the rabbets and the plate, so as to cause the outer edge of the plate to hug the inner corner of the rabbet irrespective 105 of the degree to which the plate must be flexed in order to conform to the shape of the steam-chest. The plate is provided with downwardly projecting rods 56 extending from flanges 57 riveted to the plate. The 110 adjacent longitudinal edges of the steam-chests are provided with laterally extending lips 58 59, the said longitudinal rabbets being formed in said lips. Clamp-bars 60 take under the lips. The rods 56 take through the clamp-bars and have nuts 61 screwing thereon against the clamp-bars for forcing the plate G into the rabbets and causing it to bend and take upon itself the shape to which the steam-chest and consequently its lip and 115

the walls of the rabbet may have been warped in practice, as seen in the exemplification in Fig. 5. It will thus be seen that the plate compensates for variations that 5 steam-chests may assume in practice, and that proper connection between the bed surfaces of mangle-sections is thus provided by means of a resilient bridge-piece between said sections in convenient and economical 10 manner. I prefer that the lip of the steam-chest at the feed-in-end of any given section shall project into the lateral plane of the succeeding mangle-section, as seen the lip 58 of steam-chest C of section Y in Figs. 2 15 to 5 taking beyond the meeting lines between the sides of the frames of section Y and Z.

If desired the section A may be provided with the rotating steam or heating mangle cylinder 65, journaled in bearings 66 in the 20 frame. An endless apron 67 which in practice usually has a width of about the length of the rolls hereinafter mentioned, is adapted to travel about this cylinder for carrying the goods about and pressing said goods 25 against said cylinder for ironing the same. This apron travels about suitable rolls and I have provided novel means for directing the goods with relation to it and the steam cylinder. The apron travels over a roll 68, 30 the upper face of whose periphery is preferably higher than the end lip of the steam-chest B for receiving and directing the goods from the surface of the steam-chest upon a slightly upwardly inclined stretch 35 69 of the apron, formed by said belt passing from the roll 68 to a roll 70. This roll 70 is preferably padded, that is, covered with felt or canvas or other suitable compressible covering. The apron then passes about the 40 heated cylinder and takes over a roll 71 which also preferably has a compressible covering. Then the apron passes about rolls 72, 73, 74, 75 and back to roll 68. The roll 74 is preferably a take-up roll operated in 45 suitable manner, and the roll 73 is preferably a guide-roll operated in suitable manner for guiding the apron in the proper transverse position upon the steam-cylinder.

The rolls 70 71 respectively have journal 50 ends 76 77 journaled in bearings 78 79 in guide-ways 80 81 in the frame. Each of these bearings is backed by a spring 82 taking into a hollow cap 83 for giving the said rolls resilient pressure toward the heated cylinder, a bolt 84 taking against a washer 85 above the spring for regulating its tension. (See Fig. 12.)

For guiding the goods into contact with and away from the heated cylinder, I have 60 provided novel instrumentalities. 91 is a curved guide-plate, and may be termed an intake guide whose cylinder-edge 92 (see Fig. 10) is nearer the rotary axis of said roll than the outer edge 93 of the curved

part of said plate. The outer longitudinal 65 end of said plate preferably projects at a tangent from said curved part, as shown at 94. A widened mouth 95 between said plate and the apron is thus provided for readily receiving the goods, the intake-guide gradually approaching the apron and roll 70 for directing the goods toward the heated cylinder. After passing between said plate and apron, the goods pass about the cylinder between the cylinder and apron until 75 they reach the position of the roll 71, beyond which a curved guide-plate 96 is located, the inner or cylinder edge 97 of which is closer to the roll than the outer edge 98 of the same for forming a delivery-chute 80 having an outer widened mouth 99. The cylinder edge 97 rides upon the steam cylinder and is adapted to "doff" the goods from the cylinder, forming a doffer-plate, and the gradually widening space between 85 the doffer-plate and the periphery of the roll prevents crowding or "hunching" or curling of the goods between the apron and doffer-plate. I have provided novel means for supporting or hanging said guide- 90 plates. Thus frame A is provided with an arch 101 upon which I bolt a hanger-bracket 102, there being one of these arches and brackets at each side of the machine. The brackets are provided with slots 103 104. 95 Each end of the intake guide-plate 91 is provided with a trunnion-piece 105 having a trunnion 106, and each end of the doffer-plate is provided with a trunnion-piece 107 having a trunnion 108. These trunnion-pieces have curved faces to correspond with the curving of the guide-plates, which latter are riveted thereto.

Hangers 109 110 are secured to the extensions 102, as by having bolts 111 112 take 10 through apertures in said hangers and said slots 103 104 respectively. Said hangers are provided with trunnion-bearings 113 114 which are preferably open at the top so that the respective guide-plates may be readily slipped into position by having their trunnions dropped into the trunnion-bearings of said hangers. In normal position the cylinder edges of said respective plates bear against the steam cylinder by gravity 11 owing to the manner in which they are hung. It will be noted further that by reason of the construction and manner of hanging the trunnion-hangers, the said hangers may be swung upon their bolt-connections 12 as on a pivot, or may be raised or lowered in their slots, for obtaining any desired relation between said guide-plates and their adjacent rolls and the cylinder. It will be noted further that in my improved construction, I get the benefit of almost the entire periphery of the heated cylinder for ironing purposes and bring the feeding-in and feed-

ing-out rolls, with their respective guide-
plates and means for adjusting the latter
into compact relation.

For driving the shaft 31 of section Y and
the steam cylinder, I provide an initial
drive-shaft 115, which may be driven from
a pulley 116. The shaft 115 has a pinion
117 secured thereto, which latter meshes
with a gear 118 on a shaft 119 having a pin-
ion 120 thereon meshing with the gear 32 on
shaft 31. The shaft 115 also carries a pinion
indicated at 121, which meshes with a gear
122 on a shaft 123, shaft 123 carrying
a pinion indicated at 124 meshing with a
gear indicated at 125 on the steam cylinder
shaft.

Having thus fully described my invention,
what I claim as new and desire to secure by
Letters Patent is:

20 1. In a sectional mangle, the combination
of mangle-sections comprising heating-
chests having lips extending longitudinally
of said heating chests and laterally at the
ends of said mangle-sections, a flexible plate
25 between said lips, and means taking under
said lips for forcing said plate downwardly
to conform to the longitudinal lines of said
lips.

2. In a sectional mangle, the combination
30 of mangle-sections comprising frames hav-
ing heating-chests, said heating-chests hav-
ing lips, the adjacent lips of adjacent man-
gle-sections being spaced apart, the said ad-
jacent lip of a given one of said mangle-
35 sections extending laterally into a succeed-
ing one of said mangle-sections, and a flexi-
ble plate bridging the space between said
last-named adjacent lip and the adjacent lip
of said succeeding mangle-section at one side
40 of said lips, and means at the other side of
said lips for pressing said flexible plate into
allinement with said respective lips.

3. In a mangle, the combination with a
heating cylinder, an apron taking there-
45 about, and guide-rolls for said apron, a
trunnioned plate adjacent to a guide-roll,
trunnion-hangers for said plate, and means
for swingingly supporting and permitting
bodily shifting of said trunnion-hangers.

4. In a mangle, the combination with a 50
heating cylinder, an apron therefor, and
rolls for guiding said apron comprising a
feeding-in-roll and a feeding-out roll, trun-
nioned plates between said rolls said trun-
nioned plates having trunnions located be- 55
tween said plates, hangers for said trun-
nions, and means for permitting adjustment
of said hangers.

5. In a sectional mangle, the combination 60
of mangle-sections each comprising a frame,
heating chest and opposing roll therefor, the
adjacent edges of said heating chests of ad-
jacent mangle-sections being spaced apart,
a flexible plate connecting said adjacent 65
edges, gearing mounted in each section for
driving the roll therein, an intermediate
gear journaled in one of said adjacent man-
gle-sections projecting into lateral plane of
both said adjacent mangle-sections and 70
forming connecting gear between the gear-
ing on respective adjacent mangle-sections
for driving the gearing of one of said adja-
cent mangle-sections from the gearing of the
other of said adjacent mangle-sections.

6. In a sectional mangle, the combination 75
of mangle-sections each containing a main
frame, a heating chest and an opposing roll,
means for securing said main frames to-
gether, the adjacent edges of adjacent heat-
ing-chests of adjacent mangle-sections being 80
spaced apart, each of said adjacent edges
being provided with a longitudinal rabbet,
a curved flexible bridge-piece spanning said
space and received by said rabbets, means
for rigidly securing said curved flexible 85
bridge-piece in each of said rabbets, the ad-
jacent longitudinal edges of said rabbets
normally having a space 55 between them
and the underside of said curved flexible
bridge-piece, substantially as described. 90

In testimony whereof I have subscribed
my name hereto in the presence of two sub-
scribing witnesses.
